[57] CLAIM

The ornamental design for a display rack for books,
tapes, records or the like, as shown and described.

DESCRIPTION

FIG. 1 is a perspective view of a display rack for books,
tapes, records or the like showing my new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a right side elevational view thereof; and

FIG. 7 is a left side elevational view thereof.

The rack is broken away in FIGS. 4-7 to indicate indeterminate length.
